T. A. DROZ

BRACELET LINK

Filed May 21, 1927

INVENTOR.
Theodore A. Droz
BY Barlow & Barlow
ATTORNEYS.

UNITED STATES PATENT OFFICE.

THEODORE A. DROZ, OF PROVIDENCE, RHODE ISLAND, ASSIGNOR TO ROSENHEIM COMPANY, OF PROVIDENCE, RHODE ISLAND, A FIRM COMPOSED OF PERCIVAL W. JONES, MILTON E. ROSENHEIM, AND HARRY WACHENHEIMER.

DESIGN FOR A BRACELET LINK.

Application filed May 21, 1927. Serial No. 22,123. Term of patent 3½ years.

To all whom it may concern:

Be it known that I, THEODORE A. DROZ, a citizen of the United States of America, residing at Providence, county of Providence, State of Rhode Island, have invented a new, original, and ornamental Design for a Bracelet Link, of which the following is a specification, reference being had to the accompanying drawing, forming a part thereof.

The figure is a perspective view of a bracelet link, illustrating my new design.

I claim:

The ornamental design for a bracelet link, substantially as shown.

THEODORE A. DROZ.
